his Attorney.

UNITED STATES PATENT OFFICE.

FRANZ KEILWERTH, OF CINCINNATI, OHIO, ASSIGNOR OF ONE-HALF TO
JULIUS FLEISCHMANN, OF CINCINNATI, OHIO.

SASH-FASTENER.

SPECIFICATION forming part of Letters Patent No. 727,968, dated May 12, 1903.

Application filed May 26, 1902. Serial No. 109,023. (No model.)

To all whom it may concern:

Be it known that I, FRANZ KEILWERTH, a citizen of the United States, residing at Cincinnati, in the county of Hamilton and State 5 of Ohio, have invented certain new and useful Improvements in Sash-Fasteners, of which the following is a specification.

My invention relates to sash-fasteners especially adapted for use in connection with 10 railway-car windows, and has for its object the providing of a supporting device of this character simple in construction, easily manipulated, and constructed in such a way that the person desiring to open or close the 15 sash may release the supporting device with the same hand used in raising or lowering the sash by a pressure of the thumb directed toward the sash; and my invention consists in the parts and in the construction, arrangement, and combinations of parts hereinafter 20 more fully described and claimed.

In the drawings, Figure 1 is a side elevation, partly in section, of my improved device, showing part of a car-window and its frame. 25 Fig. 2 is a vertical cross-section of the catch-releasing mechanism, taken on the line *w w* of Fig. 1. Fig. 3 is a vertical longitudinal section of the same, taken on the line *x x* of Fig. 2. Fig. 4 is a plan view of the coarse-pitch 30 screw with its wings, shank, and button. Fig. 5 is a horizontal cross-section on the line *y y* of Fig. 1, showing the relation of the catch and its receiving-plate. Fig. 6 is a horizontal cross-section on the line *z z* of Fig. 1, showing 35 the relation of the antifriction-roller and its track. Fig. 7 is a vertical cross-section of the antifriction-roller casing on the line *v v* of Fig. 6. Fig. 8 is a side elevation of the catch-receiving and track plate.

1 represents the window-frame, and 2 the sash. Preferably each jamb of the window-frame has a metal strip 3 let into and flush with the inner side of the jamb, along which the window-sash moves. The plate 3 is provided 40 with recesses 4 for receiving a pawl 5 normally pressed outwardly by a spring 6. The strip 3 is preferably of metal, having the recesses stamped into the same along one edge thereof, the other edge forming a track 45 7 for an antifriction-roller 8, hereinafter described. The pawl 5 swings on a pivot 9 in

a U-shaped metal frame 10, having outwardly-projecting flanges 11, the frame being let into a recess 12 in the window-jamb. One end of the spring 6 takes about a pin 13, the other 55 resting against an upper extension 14 of the pawl, thereby normally swinging the pawl outwardly on its pivot into the recesses in the window-frame. The upper edge of the pawl has an inclined face 15, so that the sash 60 may be readily raised without manually retracting the pawl, the inclined face causing the pawl to recede when engaging the strip between the recesses. The sash may be raised to any desirable height, my construction 65 permitting the recesses to be placed close together, so that the sash may be placed at any desirable elevation.

16 is a grip such as is ordinarily used on a car-window for raising the sash. 70

17 is a coarse-pitch screw sliding in a correspondingly-shaped socket 18 on a plate 19, secured in a recess 20 in the lower sash-rail, a recess 21 to rear of plate 19 receiving the screw when pressed. 75

22 is a shank for the screw, and 23 is a push-button for the shank. The shank 22 has a bearing 24, one half of which is at the edge of the grip 16, the other half at the end of a plate 25, secured immediately above the 80 grip to the lower sash-rail.

The screw 17 has a wing or wings 26 secured thereto, a wire 27 connecting a wing with a pawl, there being two wings shown in the drawings, with a pawl at each side of the 85 sash and with the pawls connected with the wings, respectively, of the coarse-pitch screw. The screw 17 is of sufficiently large or coarse pitch so that the wings may be turned about the longitudinal axis of the screw and retract 90 the pawls against their spring-pressure by a pressure on the screw longitudinally of that axis, forming an exceptionally convenient means and arrangement for manipulation. The button 23 is mounted on the shank so 95 that the shank may turn within the button. Simple pressure on the screw in the direction of its longitudinal axis will release the pawls, which pressure in practice is very conveniently applied, the construction being such as 100 to suggest its mode of operation to the ordinary traveler.

In order to ease the running of the sash, I provide each side with an antifriction-roller 8, mounted in a U-shaped metal frame 31, which in turn is mounted in a second U-shaped metal frame 32, a spring or springs 33 being disposed between the two and urging the inner U-shaped frame and antifriction-roller outwardly. The inner frame is caused to move in straight lines by flanges 34, extending inwardly at top and bottom of the outer frame, as shown in Fig. 7. The outer frame also has outwardly-extending flanges 35, the frames being of such form that they may be readily stamped out of metal. The frame 32 is let into a recess 36 in the sash-stile. The roller runs along the track 7, which is at one edge of the strip 3, the recesses 4 being at the other edge of the strip, so that the catches or pawls 5 and the rollers 8 may be disposed in vertical planes side by side and engage with the same strip without interference with each other's functions.

I claim—

1. In a sash-fastener, the combination with

a sash and frame, of a catch between the sash and frame for supporting the sash at various elevations with relation to the frame and a coarse-pitch screw connecting with the catch and retracting the catch by pressure on the screw longitudinally of the screw. 25

2. In a sash-fastener, the combination with a sash and frame, of a catch between the sash and frame for supporting the sash at various elevations with relation to the frame, and a coarse-pitch screw and socket for the same, 35 with a wing and a connection between the wing and catch, and a head for the screw, constructed and arranged for swinging the wing about the longitudinal axis of the screw and retracting the catch by pressure on the 40 head longitudinally of the screw.

In testimony whereof I have signed my name hereto in the presence of two subscribing witnesses.

FRANZ KEILWERTH.
